UNITED STATES PATENT OFFICE.

FRANK M. STEVENS, OF NEW YORK, N. Y.

AUTOMATIC LATHE.

SPECIFICATION forming part of Letters Patent No. 337,530, dated March 9, 1886.

Application filed April 24, 1885. Serial No. 163,242. (No model.)

To all whom it may concern:

Be it known that I, FRANK M. STEVENS, a citizen of the United States, residing at New York, in the county of New York and State 5 of New York, have invented certain new and useful Improvements in Automatic Lathes, of which the following is a specification.

My invention consists of certain mechanical devices so combined and arranged as to produce a complete automatic working lathe whereby various articles required to be either turned, milled, bored, or punched, or requiring any one or all of these manipulations or others, may be operated upon while being held 15 rigid for a limited time by a suitable clamp or its equivalent, so constructed as to be capable of receiving the article to be operated upon and releasing it only after said operations or manipulations have been completed. This I accomplish by the use of one or more revolving turrets provided with both 20 revolving and stationary tools, said turrets being mounted upon suitable sliding carriages gibbed to the lathe-bed, the various movements of the turrets and carriages being produced by means of cams, levers, and springs, the revolving tools carried in said turrets being operated by means of gearing or other 25 suitable mechanism.

30 The object of my invention is to cheapen the cost of producing various articles requiring these various operations by doing it all without the employment of hand labor.

Figure 1 is an elevation of my improved 35 automatic lathe, Fig. 2 being a plan view of the same. Fig. 3 is an enlarged section taken longitudinally, showing the turrets with their carriages mounted on the lathe-bed, the levers, spring, and a portion of the cams by 40 which they are operated, also the vertical shafts carrying the driving-gears, operating the pinions by which the revolving tools are driven and the belt-pulleys by which the power is transmitted. Fig. 4 is a transverse 45 section taken through the center of one of the turrets, showing the manner of mounting the carriage upon the lathe-bed and the turret upon said carriage. Fig. 5 is a transverse section of the feeding mechanism when in its 50 position on the lathe-bed. Fig. 6 is a front elevation of the inclined feeding-chute detached from the lathe-bed. Fig. 7 is a de-

tached front elevation of the seat or support upon which is placed the article to be operated upon. Fig. 8 is a general plan view of 55 the feeding mechanism complete bolted to a section of the lathe-bed. Fig. 9 is an enlarged perspective view of the clamping-jaw, which is adapted to slide vertically upon and in front of the seat or support shown in Fig. 60 7 and clamp the piece while being turned, bored, or punched, and also shows a section of the lever to which it is pivoted and by which it is operated. Fig. 10 is a side elevation of that cam for rotating the turret 65 which is represented at the left hand in the plan view Fig. 2. Fig. 11 represents that cam for rotating the turret which is represented at the right in the plan view Fig. 2. Fig. 12 is a side elevation of the cam 70 for operating the left turret carriage, and Fig. 13 is a like view of the cam for operating the opposite turret carriage.

The lathe-bed A is preferably formed of 75 cast iron, and may be made in any design which is conveniently adapted to carry the various parts comprising my improved machine. If constructed in accordance with my drawings, this part, looking at it in plan, is of rectangular form, having an opening 80 through from top to bottom, the sides and ends being provided at their bottom with an outwardly-projecting flange, a, of any convenient width and thickness.

Two turrets are provided, in order that both 85 ends of the article to be manufactured may be operated upon at the same time. Each of these turrets B B' is provided, respectively, with suitable journal-boxes, B² B³, for carrying the shafts for operating the various tools required to perform certain work to be herein-after described. Said turrets are mounted, respectively, upon and within the sliding carriages C C', which are adapted to slide to and fro upon the flanges a', projecting outwardly 90 from the top of either side of the lathe-bed A, gibs being provided and held in position by set-screws for taking up all looseness or slack resulting from wear, as seen best in Fig. 4.

Near either end of the bed A, and bearing, respectively, against the turret-carriages C C', are hung the levers D D', the tops of which are adapted to bear against the outer ends of

said carriages and be continually held in contact with the same by reason of the cams E E', which bear against friction-rolls d' d', mounted upon a pin passed through suitable ears formed upon and projecting from the said levers D D', about midway from either end thereof. Between said carriages C C', and reaching from one to the other, is placed the spiral spring F, which bears against said carriages and serves to force them apart, a convenient means for retaining said spring in its proper position being illustrated by the studs e e', formed upon said carriages, over which the ends of said spring may be placed.

15 The construction and mode of operation of the turrets, sliding carriages, intermediate spring with their levers and cams are best illustrated in Fig. 3 of the drawings.

The cams E E' are mounted, respectively, 20 upon the transverse shafts G G', mounted in suitable bearings on the lathe-bed A. Motion is communicated thereto respectively by the bevel-gears g g', mounted upon the front end of either of said shafts and meshing, respectively, with the bevel-gears H H', mounted upon the main shaft h, hung in suitable bearings formed upon or attached to the bed A, and provided at one end with a suitable driving-pulley, as seen in Figs. 1 and 2.

30 I do not limit myself to any one means for rotating the turrets so as to bring the different tools into position, as the mechanism must necessarily vary with the class of work this lathe may be constructed to perform. It may be 35 advisable to use for this purpose racks and pinions, various gearing, chain belts and pulleys, or the cylindrical sides of the turrets may be notched, as at b' b', to receive, respectively, the sliding pawls I I', operating laterally in or 40 upon the horizontal levers J J', guided, respectively, by the supporting-ways K K', bolted to the lathe-bed A and receiving motion from the vertical levers L L', to the tops of which they are pivoted at k k'. These levers L L' 45 may be similar to the levers D D' and hung in a similar manner and operated by means of the cams M M'. By varying the length of the said levers L L' from their fulcrum-point to the point of contact with the cams M M' 50 the rotation of the turrets B B' may be limited as required for bringing the different tools mounted upon the top thereof into line with their work.

The various tools—such as drills, polishing-tools, or milling-tools—will be placed in a chuck, and said chuck be threaded to the outer end of a shaft, b, this form of shaft being shown in Fig. 3 of the drawings, mounted in one of the journal boxes, B², and having on 55 its inner end a bevel-pinion meshing in a bevel-gear mounted upon the top of the vertical shaft N, having its bearing in the turret, and provided on its lower end with a suitable driving-pulley. Each of the turrets is fitted 60 alike, respectively, with the shafts b b', mounted in their boxes B² B³, the bevel-pinnions and bevel gears and the shafts N N' having suit-

ble driving-pulleys. Some of the bearings B² B³ are fitted in this manner, and others with various non-revolving tools, such as centering-tools, punches, and the like, which may be held in place in the said bearings by ordinary set-screws, and made to perform their function (after having been brought around to a position longitudinal with the lathe-bed by the rotary movement of the turrets) by means of the carriages C C', upon which the turrets are mounted, and to which a sudden quick motion may be imparted by the cams and levers before described.

The feeding mechanism consists of an inclined chute, O, into which the blanks to be operated upon, after being cut the proper length, are placed one above the other, as in Fig. 5. At the foot of this chute is mounted 85 a feed-roll, O', having serrations or grooves running from end to end. The object of the wheel or roll O' is to prevent the chute from emptying itself prematurely. This is accomplished by contact with the blanks X, nearest 90 the lower end of the chute, as seen in Figs. 5 and 8, and by the mechanism, to be described, whereby said blanks are passed out singly. After leaving the chute these blanks are deposited on the seat-block P, which is formed 95 as shown in Figs. 5 and 7, and the moment it is fairly deposited thereon the adjustable jaw Q drops upon it and holds it firm as a vise, and while being so held the various tools in the turrets are doing their work. 100 The adjustable jaw Q is held close to the seat-block P, and allowed a vertical movement thereon by the screw bolt p, which passes through the slotted opening Q', (shown in Fig. 9,) thence through a hole in the seat-block P, 105 and terminates in the metal supporting the chute O. (Seen in Figs. 5 and 6.) This jaw Q is pivoted at its bottom to the forked lever R, fulcrumed at R' to the chute-frame, as in Figs. 5 and 8, said forked lever extending 110 thence laterally forward and over the driving-shaft h, at which point it rests in a shoe, S, provided underneath with suitable ears, s, between which is pivoted a friction-roll, s', bearing upon the cam T, mounted, as shown, upon 115 the driving-shaft h. The outer end of the forked lever R carries the weight U, which may be one hundred pounds (more or less.) The shoe S may be secured in its proper position by a set-screw, s', as in Fig. 8.

The operation of this feeding mechanism is as follows: The direction of the rotation of the cam T is shown by the darts in Fig. 5, and when the ridge t passes under the friction-roll s the lever R and the jaw Q are caused to rise. 125 This movement rotates the feed wheel or roll O' just one notch by reason of the latch V, which is pivoted at v to the top of the jaw Q, its free end being provided with a laterally-projecting stud, V', adapted to fit into either of 130 the grooves or serrations in said feed-roll O'. If necessary, said feed-roll may be provided with a ratchet and pawl or other means for preventing its rotation, except when done by

said latch V, and said latch may be prevented from flying out from the grooves in said feed-roll by a suitable spring, if desired so to do. Side plates, Q², will straddle the seat-block P, 5 and thus guide the jaw Q during its vertical movement, and, if desired, a die-plate containing any necessary inscription may be fitted to the groove Q³. (seen in the perspective view of this piece, Fig. 9,) and every time said 10 jaw comes down upon a blank said inscription will be embedded therein.

The chute O may be made of different widths in conformity to different classes of work or work of different lengths. The base- 15 plate o of said chute O is bolted, as seen in Figs. 5 and 8, to the flanges a², projecting out from the flanges a¹ of the lathe-bed A.

From the foregoing it will be understood that the sliding carriages are not dependent 20 upon the actuating-levers D D' for receiving motion, as the cams E E' can be arranged to operate directly upon said carriages with equally as good results. Either or both of the said carriages C C' may be operated by 25 cams, or by the cams and actuating-levers, as before stated, and each or both be so varied in their construction as to be adapted for carrying various tools or the work to be operated upon independent of the revolving turrets, 30 and thus serve a good purpose upon other than turret-lathes.

Having described the construction of my improved lathe in order to illustrate its operation, I will now describe its adaptation to 35 the manufacture of one article—viz., a watch-key—for which I have previously made application for a patent in the United States. Said key is about one and one-quarter inch in length, and one-quarter inch (more or less) in 40 diameter, the end in which the socket is formed being tapered, as are the stems of ordinary watch-keys. Said key may be formed cylindrical, hexagonal, or octagonal, and in its longitudinal center a hole is bored, connecting the opposite end to that in which the 45 socket is formed with the inner terminus of said socket for the purpose of blowing the dust or dirt therefrom, and thus keeping the socket free.

50 The wire from which the keys are to be made, after being formed octagonal or cylindrical, as may be desired, is first cut the proper length for the keys. Then these blanks are placed in the inclined chute O, as seen in Fig. 5 of the 55 drawings, and by means of the corrugated wheel O', rotated by the mechanism, as previously described, said blanks are let off one at a time and landed on the seat-block P and held firmly thereon by the jaw Q. Now, we will 60 suppose the turret B to carry in its boxes B² four tools—viz., a center punch, a drill, a square punch, and a hollow boring tool or mill—and the turret B' to carry in its boxes B³ three tools—viz., a center punch, a drill, 65 and a finishing-tool. As soon as the jaw has dropped onto the blank the center punch in each turret will be in line with said blank and

ready to be moved forward by means of the cams operating the sliding carriages C C'. After the blank has been centered and the said 70 carriages returned to their former positions the cams for operating the turrets will rotate said turrets sufficiently to bring the drills in line with said blank. The carriage C is then first moved toward the blank, and the drill mounted on the turret B bores the hole for the socket. Subsequently the carriage C' is again moved toward the blank, and the drill mounted on the turret B' bores the hole connecting with the socket-hole, after which the 75 carriages are again moved away and the turrets rotated until the square punch on the turret B and the finishing-tool on the turret B' are in line with said blank, and when the carriages again move toward said blank the 80 square punch forms the square socket, while the tool on the opposite turret finishes that end of the key. There then remains but one 85 operation to complete the key—i. e., turning the taper on the socket end—which is accomplished by the fourth tool on the turret B. After this last operation the jaw Q rises by aid of the cam T and weighted lever R and releases the finished key and receives a second 90 blank.

The finished key may be shot out, if desired, after the upward movement of the jaw Q by a suitable tool held in either of the turrets B B' and operated as are the other stationary tools.

The speed of the shaft h and the construction of the cam T are such as to insure the retention of a blank under the jaw Q while all of the several above operations are being performed.

Having described my invention, what I 105 claim as new, and desire to secure by Letters Patent, is—

1. The combination of a lathe-bed having mechanism, substantially as described, for holding the work rigid, the sliding carriages, 110 and revolving turrets, with longitudinal and transverse shafts hung in bearings on said bed and connected by bevel-gears, and suitable cams and actuating-levers, whereby said turrets are rotated and said carriages are moved 115 as required, all constructed and operating substantially as and for the purpose specified.

2. The combination of a lathe-bed having mechanism, substantially as described, for holding the work rigid, the sliding carriages, and 120 revolving turrets, stationary tools mounted radially thereon, with longitudinal and transverse shafts hung in bearings on said bed and connected by bevel-gears, and suitable cams and actuating-levers, whereby said turrets are 125 rotated and said carriages are moved upon said bed as required, all constructed and operating substantially as and for the purpose set forth.

3. The combination of a lathe-bed having 130 mechanism, substantially as described, for holding the work rigid, the sliding carriages and revolving turrets, revolving tools mounted radially thereon, and means, substantially as

shown, for driving the same, with longitudinal and transverse shafts hung in bearings upon said lathe-bed and connected by bevel-gears, and suitable cams and actuating-levers, whereby said turrets are rotated and said carriages are moved upon said bed as required, all constructed and operating as and for the purpose set forth.

4. The combination of a lathe-bed having mechanism, substantially as described, for holding the work rigid, the sliding carriages and revolving turrets, revolving tools mounted radially thereon and driven by bevel-pinions, and a bevel-gear mounted on a vertical shaft hung centrally in said turrets and having at its lower end a belt-pulley, with longitudinal and transverse shafts hung in bearings upon said lathe-bed and connected by bevel-gears, and suitable cams and actuating-levers, whereby said turrets are rotated and said carriages are moved upon said bed as required, all constructed and operating substantially in the manner and for the purpose described and set forth.

5. In a lathe, the combination of a sliding carriage and a revolving turret mounted thereon and provided with revolving tools, and means, substantially as described, whereby said carriage and turret are moved and rotated intermittently, as set forth.

6. In a lathe, the combination of a weighted lever, a cam for operating said lever, a movable jaw, a latch, a feed-wheel, and a chute, all arranged to operate as an automatic feeding device substantially as shown, and for the purpose set forth.

7. In a lathe, the combination of a movable

jaw, a seat-block, a lever connected with said jaw, and means for operating the same, whereby the work may be held rigid while being operated upon, substantially as shown and described.

8. In a lathe, the combination of a movable jaw provided with a groove for the insertion of a stamping die, a seat-block, a lever connected with said jaw substantially as shown, and means for operating the same, whereby the work may be stamped or marked while being held to be operated upon, as and for the purpose set forth.

9. In a lathe, the combination of revolving turrets and sliding carriages, and a cam for moving said carriages, substantially as described, with a spring, for the purpose of moving and holding said carriages in close contact with said cam, as shown and set forth.

10. In a lathe, the combination, with a sliding carriage, of a revolving turret, and revolving tools mounted thereon, and means, substantially as described, whereby said turret may be revolved independently of said carriage, as set forth.

11. In a lathe, the combination, with sliding carriages, of revolving turrets having notches or ratchets $b^2 b^3$, pawls $I I'$, and means, substantially as described, whereby said turrets may be revolved independently of said carriages, as and for the purpose set forth.

In testimony whereof I affix my signature in presence of two witnesses,

FRANK M. STEVENS.
